UNITED STATES PATENT OFFICE.

JAMES BURKE, OF ERIE, PENNSYLVANIA, ASSIGNOR TO BURKE ELECTRIC COMPANY,
A CORPORATION OF PENNSYLVANIA.

TRANSFORMER.

1,145,551.

Specification of Letters Patent.

Patented July 6, 1915.

Application filed December 10, 1910. Serial No. 596,731.

To all whom it may concern:

Be it known that I, JAMES BURKE, a citizen of the United States, residing at Erie, in the county of Erie and State of Pennsylvania, have invented certain new and useful Improvements in Transformers, of which the following is a full, clear, and exact specification.

This invention relates to transformers, induction coils, and the like, and pertains particularly to the construction and arrangement of the cores of transformers and the like.

My invention relates further to the method of constructing the same.

More specifically, my invention relates to cores formed of laminæ or sheets of magnetic material, said laminæ or sheets being constructed to insure effectively good magnetic contact at the joints of the laminæ or sheets so that all air gaps are substantially avoided.

By my invention, I construct a transformer core applicable to transformers having any desired number of legs any of which may either be provided or not provided with transformer winding or windings as desired, and which legs are united at their ends by end pieces in which the laminæ are continuous throughout the length of the end pieces, while at the same time obtaining overlapping form of joints with the attendant advantages of such form of joints.

My invention will be more fully understood from the following description and accompanying drawings, in which—

Figure 1 is a perspective view of assembled legs and end pieces constituting a core, embodying one form of my invention. Fig. 2 is an end elevation of an individual core leg of the same; and Fig. 3 is a side elevation of the same.

The core comprises two or more legs and end members uniting the legs at their respective ends. Taking the form of leg construction shown in Figs. 2 and 3 the laminæ are arranged one adjacent the other to provide projecting portions at both ends. In the specific form shown in said Figs. 2 and 3, the laminæ 6, 7 are of equal length, alternatively arranged to provide equal projecting portions at the two ends. It is not necessary that said laminæ 6, 7 be of the same dimensions, since, as will be readily understood, each leg may be formed of alternate

sets of short and longer laminæ and staggered relatively to each other to provide either equal or unequal projecting portions, which portions, as will be later more fully seen, overlap corresponding lateral projecting portions of the end members. The end pieces or members are built up of continuous laminæ extending from one end of one leg to a corresponding end of the other leg or corresponding ends of the remaining legs.

As shown in Fig. 1, the continuous end members 4, 5 extend from the upper and lower ends, respectively, of leg 1 across the ends of intermediate leg 2 to the corresponding ends of outermost leg 3. These members 4, 5, as shown, comprise each two sets of laminæ 9, 10 of different widths, arranged one adjacent the other to give a lateral stagger, the difference in width in this specific form being equal to the amount of stagger or length of the projecting portions of the laminæ on the ends of the legs 1, 2, 3 at which they are positioned.

Said end pieces or members 4, 5 may be built up of laminæ of the same dimensions, whereby projecting portions of alternate laminæ will extend upwardly in the upper end member 4, and likewise downwardly in the lower end member 5. In general, assuming the effective total amount of magnetic material of the laminæ to be proper according to the requirements of the transformer, each end member is built up of laminæ arranged in sets to provide lateral inter-lamellar spaces into which the projecting portions at one end of each leg make a good fit, each lamina of continuous material of each end piece being brought into good magnetic contact edge for edge with the isoplanar lamina of each leg, whereby the projecting portions at the ends of the legs make overlapping joints with the lateral projecting portions of the end pieces. The amount of stagger between adjacent sheets or laminæ of the legs and end pieces may be varied, but in all cases the amount overlapping is preferably made small, but sufficient to give the necessary grip and strength.

Any suitable means may be employed for binding the laminæ of the end members, and I have shown strips 11 of wood or other suitable material applied to the outermost laminæ on the opposite sides of each end piece, and bound in such position by cord 12.

In assembling my transformer, the legs are first constructed as above stated, the

laminæ of each individual leg being bound together as a unit by tape or other suitable bandage. These legs are then placed at proper distances from each other with corresponding projections in or approximately in the same plane. My preferred method of uniting the corresponding ends of the legs by the continuous end pieces, is to build the end pieces in sequence, inserting first those 10 laminæ of one end piece, say laminæ 10 of end piece 4, into the isoplanar grooves of the legs 1, 2, 3, bringing each lamina 10 in effective magnetic contact with the isoplanar laminæ of the legs. After all of the 15 laminæ 10 of end piece 4 are thus positioned, the laminæ 9 are then inserted between alternate laminæ 10, and likewise positioned in good magnetic contact with the upper edges of laminæ 6 of the legs 1, 2, 3. The 20 end piece 5 is built in a similar manner. It will be understood that in such cases where the transformer winding or windings are wound about any desired leg, such as indicated at 8, it is convenient to wind the same 25 before either end piece is positioned; when the winding or windings are of the "slip-on" type, the same can be slipped on the desired leg at any time before the last end piece is positioned. It will thus be seen that 30 my transformer is applicable for any number of legs, whether or not the same are provided with a transformer winding, with the advantages of overlapping joints, while having continuous strips throughout the length 35 of the end pieces, and at the same time securing rigidity in construction and ease and

simplicity in assembling and economy of material.

Having thus described my invention, I declare that what I claim as new and desire to secure by Letters Patent, is,—

1. A transformer core of magnetic material comprising a plurality of legs, each of said legs being built up of laminæ, each lamina thereof being a rectangle, and said laminæ being assembled to form projections and intermediate grooves at the ends of the legs, and laminated end pieces, each lamina of the end pieces extending to the outermost edges of the legs, and the laminæ of the end pieces assembled to form projections and grooves which face and fit the projections and grooves of the ends of the legs.

2. A transformer core of magnetic material comprising a plurality of legs, each of said legs being built up of laminæ, each lamina thereof being a rectangle, and said laminæ being assembled to form projections and intermediate grooves at the ends of the legs, and laminated end pieces, each lamina of the end pieces being a rectangle and extending to the outermost edges of the legs, the laminæ of the end pieces being assembled to form projections and grooves which face and fit the projections of the end of the legs.

In testimony whereof I affix my signature, in presence of two witnesses.

JAMES BURKE.
